UNITED STATES PATENT OFFICE.

ALFRED H. HELDEN, OF KANSAS CITY, MISSOURI.

COMBINED FIXED-ANGLE SQUARE AND PROTRACTOR.

1,365,991.

Specification of Letters Patent. Patented Jan. 18, 1921.

Application filed February 28, 1919. Serial No. 279,689.

To all whom it may concern:

Be it known that I, ALFRED H. HELDEN, a citizen of the United States, residing at Kansas City, in the county of Jackson and State of Missouri, have invented certain new and useful Improvements in Combined Fixed-Angle Squares and Protractors; and I do declare the following to be a full, clear, and exact description of the invention, such as will enable others skilled in the art to which it appertains to make and use the same.

This invention relates to geometrical instruments, and it relates more specifically to an improved combined fixed-angle square and protractor.

One object of the invention is to provide a device of this character which is extremely convenient and thoroughly practical for laying off angles on rafters, braces, stairs, etc.

A further object is to provide an adjustable device of this character with which the angles of both the top and bottom cuts of a rafter may be laid off while the adjustment of its parts remains unchanged.

Another object is to provide a device of this character which simultaneously indicates the degree of angularity and the pitch or rise in inches per foot.

Another object is to provide a device of this character which comprises a square having an improved fraction-index thereon to coact with the base in indicating the fractional pitch of one line relative to another line.

Other objects and advantages may become apparent to persons who read the following details of description in connection with the accompanying drawings, in which:

Figure 1 is a side elevation showing my improved geographical instrument applied to a beam which is to be laid off and scribed.

Fig. 2 is an enlarged front elevation of the device, the blade and wing of the square being broken off.

Fig. 3 is an enlarged rear elevation of the device, except being shown with the square in a different position from that shown in Fig. 2.

Fig. 4 is a sectional view along the line 4-4 of Fig. 2.

Fig. 5 is a sectional view along the line 5-5 of Fig. 2.

Fig. 6 is a sectional view along the line 6-6 of Fig. 2.

Fig. 7 is a detail view illustrating the

angular element or square detached from the base of the device.

Referring to these drawings in detail, in which similar reference characters correspond with similar parts throughout the several views, the device broadly consists of a base 10, an angular element or square 11, and a pivot 12 which unites the square with the base. The base preferably consists of two plates 13 and 14 which are L-shaped in cross section, and a flat plate 15, the latter being embraced between the plates 13 and 14, and these three parts are secured together by rivets 16 or by other appropriate means. Each of the members 13 and 14 is provided with a flange which extends from end to end thereof, and the surfaces 17 of these flanges are straight and disposed in the same plane. Each of these surfaces 17 constitutes a working face of the base member as will be seen by reference to Fig. 1. The bar or plate 15 is formed with a semi-circular recess 18 around which is a segmental or arcuate scale 19, and each of the members 13 and 14 is formed with an aperture or bearing 20 which is concentric with the arcuate scale 19. One segmental portion of the scale 19 is provided with graduations and numerals to indicate degrees of angularity, as shown at 21, another portion of the scale being graduated and numbered to indicate units of linear measure, inches being indicated in the present instance, as shown at 22.

The square or angular element 11 has its outer edges 23 and 24 parallel with the corresponding inner edges 25 and 26, and the outer edges, if produced, would pass through the center of the segmental scale 19, this center being spaced from the working faces 17 a distance equal to the distance between the edges 23 and 25 of the square. The inner edge 27 of the plate 15 is also spaced from the working faces 17 a distance equal to the distance between the edges 23 and 25, so that when the edge 23 is against the edge 27, the edge 25 is flush with the working faces 17, and the edge 24 is at right angles to the length of the faces 17, as here shown in Fig. 3.

The angular element 11 is formed with an index element 28 which extends outwardly therefrom and terminates in two indexing points or indicating pointers 29 and 30. The index 28 is disposed within the semi-circular recess or aperture 18, and each

indexing point is in alinement with one of the outer edges 23—24, the other indexing point being in alinement with the other one of said outer edges. The pivot 12 extends 5 through an aperture 31 at the apex of the angle formed by producing the edges 23—24, and the center of this aperture is directly between the point 29 and the edge 24, being also directly between the point 30 and edge 10 23. It will be seen, therefore, that when the instrument is adjusted as shown in Fig. 3, the indexing point 30 registers with a point 15 on the scale which may be properly termed the zero point of the arcuate or segmental graduation 21. However, this zero point for the edge 26 is also the 90° point for the edges 23 and 25, that is, as shown in Fig. 3, when the indexing point 30 registers with the mark at the beginning of the scale or 20 graduation 21, it indicates that the edge 26 is flush or parallel with the working faces 17 and that the edges 23 and 25 are at right angles thereto; but, when the indexing point 30 is moved upward along the scale 21 it 25 indicates the degree of angularity between the working surfaces 17 and the edges 24 and 26. Although I have spoken of the index or graduation 21 in the singular, it will be seen, by referring to Figs. 2 and 3, that 30 the scale 21 is duplicated on opposite sides of the plate 15, and the same is true regarding the scale 22. Referring now more specifically to the scale or graduation 22, it is seen that the same is arranged for indicating 35 the amount of pitch as referred to the surfaces 17 and the edges 23 and 25. In other words, this scale indicates the number of inches "rise" for each foot of "run" along a beam to be laid off. Although this scale 40 indicates but 18 inches of rise, it will be seen that the scale may be increased to 24 inches rise, if desired, without conflicting with or overlapping the scale 21.

The square is provided with outwardly 45 diverging lines 32 which coact with the working faces 17, in a well known manner, for indicating the fractional pitch, thus $\frac{1}{4}$ pitch, $\frac{1}{3}$ pitch, $\frac{1}{2}$ pitch, etc., as indicated at 33. In order to avoid confusion of the fractions 50 33, with the lines 32 which are not intended to be designated by these fractions, the latter are placed in a column at a distance from the terminals of the lines 32, and curved lines 34 connect the respective fractions with the lines 32 intended to be designated, respectively, thereby.

The pivot 12 is preferably in the form of a screw, and a wing nut 34' is provided on the screw and co-operates therewith and with 60 the somewhat yieldable bars 13 and 14 for effecting a clamping or frictional engagement with the opposite sides of the square, so that the latter may be held thereby in its respective adjustments.

65 From the foregoing disclosure of the con-

struction and operation of the device, it will be seen that this device is useful in many relations and for many purposes, including the laying off of beams according to angular measure, or according to a pitch in inches 70 per foot, or according to fractional pitch. This enables a person to use the device, without the necessity of resorting to mathematics where the pitch is given in degrees of angular measure, or in inches per foot, or in 75 fractions.

In order that the utility of this device may be extended still further, a spirit level 35 is provided, the index elements of this level being arranged to register when the 80 surfaces 17 are level. By this means, the device may be employed for ascertaining whether a beam or surface is plumb, level, or inclined at any angle, the degree of inclination being determined by the co-operation 85 of this level with the indexing points and other features of the instrument.

Although I have described this embodiment of my invention very specifically, it is not intended to limit this invention to these 90 exact details of construction and arrangement of parts, but I am entitled to make changes within the scope of the inventive ideas disclosed in the foregoing description and following claims.

95 What I claim as my invention is:

1. In a geometrical instrument, a base provided with a working face and a segmental scale having its center spaced from said face, an element having straight-edged 100 blades fixed at an angle to each other, this element being pivoted at the intersection of the outer edges of said blades to said base at the center of said segmental scale, said element having an indicating pointer in alinement with one of said edges and movable over said scale.

2. The structure defined by claim 1, and a second indicating pointer in alinement with another one of said edges which is at an angle 110 to the first said one of the edges, said scale comprising separate sets of graduations that coact with said edges respectively.

3. The structure defined by claim 2, one of said sets of graduations consisting of units 115 of length, the other of said sets consisting of units of angular measure.

4. The structure defined by claim 3, one of said sets of graduations including a zero on a line that intersects said working face at right angles and also intersects the pivotal axis of said adjustable element, said base and adjustable element being provided with means to confine movement of one of said indicating pointers within the arcuate 120 limits of its set of graduations.

5. In a geometrical instrument, a base provided with a working face and a segmental scale, and an adjustable element including two outer edges fixed at right angles 130

to one another and two inner edges parallel with said outer edges respectively, said adjustable element also comprising an indicating pointer in alinement with one of said outer edges, said adjustable element being pivotally connected to said base at a point at the center of curvature of said scale, said center being spaced from said working face a distance equal to the distance between two 10 of the parallel edges of said adjustable element so that the inner one of these two

edges is flush with said working face when the outer one of the other two parallel edges is at right angles to said working face, said scale having a zero in the position to register with said indicating pointer when the last mentioned outer one of these edges is at right angles to said working face. 15

In testimony whereof I have hereunto set my hand.

ALFRED H. HELDEN.
